UNITED STATES PATENT OFFICE.

JOHN H. EGLER, OF KNOXVILLE, PENNSYLVANIA.

CARPET-STRETCHER.

SPECIFICATION forming part of Letters Patent No. 468,333, dated February 9, 1892.

Application filed March 13, 1891. Serial No. 384,937. (No model.)

To all whom it may concern:

Be it known that I, JOHN H. EGLER, a citizen of the United States, residing at Knoxville, in the county of Allegheny and State of Pennsylvania, have invented certain new and useful Improvements in Carpet-Stretchers; and I do hereby declare the following to be a full, clear, and exact description of the invention, such as will enable others skilled in the art to 10 which it pertains to make and use the same, reference being had to the accompanying drawings, which form a part of this specification.

My invention relates to an improved carpet-stretcher; and it consists in certain details of construction and combination of parts, as will be fully described hereinafter.

In the accompanying drawings, Figure 1 is a plan view of my improved carpet-stretcher, 20 which is constructed in accordance with my invention. Fig. 2 is a sectional elevation of the same. Fig. 3 is an end elevation of the rear cross-brace. Fig. 4 is an enlarged side elevation of the device for attaching the rear 25 extensions together.

To put my invention into practice I provide a frame 1 of a suitable size and form of construction and mount therein in suitable bearings 2 a shaft 3, to which is secured a lever 30 5, provided with pawl 6. Operating beneath this frame 1 is a rack-bar 7 capable of being moved in the direction of the length of the said frame, and to which is affixed the top portion of an ordinary pair of tongs 13, the 35 other portion being loosely pivoted thereto and provided with a means 8 for clamping the two portions together for the purpose of taking hold of the carpet. Arranged at the forward portion of the frame 1 is a spring-pawl 40 9, which engages with the rack 7 to prevent any backward movement of the same. I now provide a number of rear braces, each consisting of two side pieces 10, provided at their extremities with a mortise and a fixed pin 11 45 or circular opening, which serves as a means of connecting the several sections together and also to attach suitable cross-brace pieces 12 to keep the side pieces parallel.

In operation the carpet is clamped between the jaws of the tongs 7 and the rear braces 50 adjusted from the frame 1 to one of the walls of the room. The lever 5 is operated back and forth, which, by means of the pawl 6, moves the rack-bar 7 forward, and it is held in that position by the spring-pawl 9, thereby 55 stretching the carpet.

Having thus described my invention, I claim—

1. In a carpet-stretcher, the combination, with the frame, a shaft journaled therein, a 60 rack-bar, a lever secured to said shaft and connected with said rack-bar, and a spring-pawl forward of said lever engaging said rack-bar and preventing rearward movement thereof, of a series of adjustable braces at the 65 rear end of said frame, each of said braces consisting of two side pieces having mortises at their rear ends and diagonal braces, all substantially as described, and for the purposes set forth.

2. The herein-described carpet-stretcher, comprising, in combination, a rectangular frame, a shaft extending transversely thereof and journaled at its ends therein, a lever mounted on said shaft, a longitudinal rack-bar, tongs at the forward end of said rack-bar, means for clamping the jaws of said tongs together, a pawl pivoted to said lever and engaging said rack-bar, a spring-pawl pivoted to the forward end of said frame, and 75 a series of adjustable braces at the rear end of said frame, consisting of side bars having mortises and pins at their rear ends and diagonal braces, all substantially as described, and for the purposes set forth.

In testimony that I claim the foregoing I hereunto affix my signature this 11th day of February, A. D. 1891.

JNO. H. EGLER. [L. S.]

In presence of—

CHARLES LARGE,
M. E. HARRISON.
